[57] **CLAIM**

The ornamental design for a hairsetter, as shown and
described.

DESCRIPTION

FIG. 1 is a perspective view of the hairsetter showing
my new design with the cover displaced from the base;
FIG. 2 is a side elevational view thereof with the cover
closed;

FIG. 3 is a top plan view thereof;
FIG. 4 is a front elevational view thereof;
FIG. 5 is a bottom plan view thereof; and
FIG. 6 is a top plan view of the hairsetter with the
cover removed.

The broken line showing of electrical sockets for rollers
in FIG. 6 is for illustrative purposes only and forms no
part of the claimed design.

FIG. 1

FIG. 2
